CHARLES BARTON WHITTEMORE, OF BOSTON, MASSACHUSETTS.

Letters Patent No. 68,402, dated September 3, 1867.

IMPROVED MODE FOR RECOVERING LOST ANCHORS.

The Schedule referred to in these Letters Patent and making part of the same.

TO ALL WHOM IT MAY CONCERN:

Be it known that I, CHARLES BARTON WHITTEMORE, of Boston, in the county of Suffolk, and State of Massachusetts, have invented an Improved Mode of Recovering Lost Anchors; and I do hereby declare the following to be a full, clear, and exact description thereof, reference being had to the accompanying drawings, making part of this specification, in which—

Figure 1 is a view showing a vessel riding at anchor, the latter being attached to a buoy aboard the vessel by lines passing through the anchor-ring.

Figure 2 shows an anchor-cable which has parted from a vessel, and which is attached to a buoy.

Figure 3 is a top view, showing the ratchets and drums for receiving and paying out the buoy-lines, which are attached to the anchor and cable.

Figure 4 is a perspective view, showing a mode of drawing a cable through the ring of an anchor, preparatory to raising the latter.

Similar letters of reference indicate corresponding parts in the several figures.

The object of this invention is to provide a vessel with means by which anchors can be easily recovered should they part their cables at any point between the windlass and anchor-ring.

The nature of my invention consists in the employment of supplemental anchor-lines, which are wound upon suitable paying-out drums, and passed through the anchor-rings, so that in casting an anchor the lines will pay out with the anchor-cable, and, should the latter part, the lines will run off their drum, and carry overboard a buoy that will mark the spot where the anchor parted, as will be hereinafter described.

It also consists in so applying supplemental lines to an anchor, said lines having a buoy or float attached to them, that should the cable part at a point below the surface of the water, another cable can be readily sent down and drawn through the anchor-ring, by which the anchor can be recovered, as will be hereinafter described.

To enable others skilled in the art to understand my invention, I will describe its construction and operation.

In the accompanying drawings, A represents a common anchor, and α the ring thereof, to which the cable B is securely fastened. The cable passes through the hawse-hole b to and around the windlass C in the usual well-known manner. To each davit D, inside of the gunwales, I apply a drum, E, having a ratchet-wheel, c , on one end, into the teeth of which a pawl, d , engages. This pawl will allow the drum to pay off its lines $g g$ freely, but will prevent the drum from turning backward when not required to do so. The lines $g g$, which are wound upon the drum E, are not permanently secured to it, but will run entirely off should the anchor-cable part. These lines $g g$ are carried through the hawse-hole along with their cable B, and passed through the anchor-ring, after the manner of applying a pulley-rope to its block. At a suitable point the lines $g g$ are attached to the cable B by a slip-loop at i , said loop being fastened to cable, so that, should the cable break or part between this loop and the vessel, there will be a surplus of cable above the loop. This loop attachment will admit of the recovery of the anchor by the old cable by simply drawing up, by means of the lines $g g$, the end of this old cable. Should the anchor-cable part at a point which is below the water, that is to say, should it part between the loop i and the anchor, a new cable must be used, which is passed down and drawn through the anchor-ring by means of the lines g .

To mark the place of the anchor I employ a buoy, G, of suitable form and size, which is attached to the lines g by means of a rope, h , of proper length, so that, when an anchor-cable parts, and the vessel floats from the place, the lines $g g$ will run off their drum or drums, and carry overboard the buoy G, so that persons can afterward return, find the buoy, and raise the anchor. As hereinbefore stated, the lines $g g$ are applied to the ring of the anchor, so that they may be drawn back and forth through it, like the movement of a rope through a pulley-block; consequently it will be seen that when the buoy is found, and the lines g drawn up, a cable may be sent down and drawn through the ring of the anchor, as shown in fig. 4, by which cable the anchor can be raised and recovered.

It will not be necessary to employ a second cable if the anchor-cable parts at a point above the loop i , for, in this case, the end of the cable can be drawn up by means of the lines $g g$; but should the cable break below the loop, then the second cable must be used as stated.

The buoys G may be stowed away in convenient places near the bow of the vessel, so as to be out of the

way, and so as to be drawn overboard when an anchor parts its cable. The lines which attach the buoys to the lifting lines *g g* are passed over the gunwales, and attached to these lifting-lines after the anchor is dropped and its cable paid out ten or fifteen fathoms more than the depth of the water.

Each one of the drums or reels E upon which the lifting-lines are wound should be of such size as to contain all the buoy-line; and the ratchet and pawl should be so constructed and applied to each drum as to prevent the weight of the lines and force of water from unreeling the lines. A crank may be used for winding the lines upon the reels or drums when the pawls are raised from their ratchet-wheels. The reels may be portable or stationary, as circumstances require.

Having described my invention, what I claim as new, and desire to secure by Letters Patent, is—

1. The supplemental lifting-line, in combination with an anchor-cable, said line being passed through the anchor-ring or its equivalent, and so arranged as to be paid out with the anchor-cable, substantially as described.
2. The buoy, in combination with the supplemental lifting-line, applied to the anchor and its cable, substantially as and for the purposes set forth.
3. The combination of the lifting-line *g*, anchor-cable B, and loop *i*, or its equivalent, substantially as and for the purposes set forth.

Witness my hand in the matter of my application for a patent for a mode of recovering lost anchors.

CHARLES BARTON WHITTEMORE.
